CLAIM

The ornamental design for a toilet tissue dispenser as shown and described.

DESCRIPTION

FIG. 1 is a perspective top front right view of a toilet tissue dispenser, showing my new design;

FIG. 2 is a perspective top rear left view thereof;

FIG. 3 is a front elevation view thereof;

FIG. 4 is a rear elevation view thereof;

FIG. 5 is a left elevation view thereof, wherein the right elevation view is an identical image thereof;

FIG. 6 is a top plan view thereof, wherein a bottom plan view is an identical image thereof; and,

FIG. 7 is a sectional view along the line 7-7 (please see FIG. 1) thereof.
